(57) **CLAIM**

The ornamental design for an aircraft, as shown and described.

DESCRIPTION

FIG. 1 is a perspective view of an aircraft showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the aircraft in a folded state;

FIG. 10 is an enlarged view of the aircraft shown within the area designated as 10 in FIG. 1;

FIG. 11 is an enlarged view of the aircraft shown within the area designated as 11 in FIG. 1;

FIG. 12 is an enlarged view of the aircraft shown within the area designated as 12 in FIG. 1;

FIG. 13 is an enlarged view of the aircraft shown within the area designated as 13 in FIG. 1;

FIG. 14 is an enlarged view of the aircraft shown within the area designated as 14 in FIG. 2; and,

FIG. 15 is an enlarged view of the aircraft shown within the area designated as 15 in FIG. 2.

The broken lines in the drawings are for the purpose of illustrating portions of the aircraft that form no part of the claimed design. The dot-dashed broken lines in FIGS. 10-15 show the boundary of the enlarged view and forms no part of the claimed design.

1 Claim, 15 Drawing Sheets
